UNITED STATES PATENT OFFICE

107,520

DESIGN FOR A CUSHION

John Herbert Johnson, Toronto, Ontario, Canada, assignor to K & W Rubber Corporation, Delaware, Ohio

Application August 16, 1937, Serial No. 71,104

Term of patent 14 years

To all whom it may concern:

Be it known that I, John Herbert Johnson, a subject of the King of Great Britain and resident of the city of Toronto, county of York, Province of Ontario, in the Dominion of Canada, have invented a new, original, and ornamental Design for a Cushion, of which the following is a specification, reference being had to the accompanying drawing, forming part thereof.

The drawing represents a perspective view of the cushion showing my new design, the serrated edges continue along the two sides not shown.

I claim:

The ornamental design for a cushion, as shown and described.

JOHN HERBERT JOHNSON.
